CLAIM

The ornamental design for telephone handset or similar article, as shown and described.

DESCRIPTION

FIGS. 1 and 2 are respectively front and rear elevational views of a telephone handset or similar article showing my new design;

FIG. 3 is a left side elevational view thereof;

FIG. 4 is a right side elevational view thereof; and

FIGS. 5 and 6 are respectively top and bottom plan views thereof;

The showing of cord in fragmentary form is for purpose of facility of illustration.
